UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FOLDER FOR SEWING-MACHINES.

1,207,977.

Specification of Letters Patent. Patented Dec. 12, 1916.

Application filed January 5, 1912. Serial No. 669,567.

To all whom it may concern:

Be it known that I, JAMES R. MOFFATT, a citizen of the United States, residing at Chicago, in the county of Cook, State of Illinois, have invented certain new and useful Improvements in Folders for Sewing-Machines, of which the following is a description, reference being had to the accompanying drawing and to the figures of reference 10 marked thereon.

The invention relates to new and useful improvements in folders, and more especially to folders used in connection with sewing machines for folding and inverting 15 a binding strip, and directing the same to a stitching mechanism, whereby an edge of fabric may be covered.

An object of the invention is to provide a folder of the above character, which may be 20 quickly threaded and which is provided with devices for folding the raw edges of the strip back upon the body portion of the strip, so that when said strip is inverted, 25 said raw edges will be concealed beneath the binding strip.

In the drawings, which show by way of illustration one embodiment of the invention,—Figure 1 is a perspective view of the folder, showing also the manner of directing 30 the folded strip to a fabric, and the relation of the folder to the stitching mechanism; Fig. 2 is a plan view of the same, with parts of the folder broken away at the receiving end thereof; Fig. 3 is a sectional view on the 35 line 3—3 of Fig. 2; and Fig. 4 is a perspective view of the receiving end of the folder, showing the manner of folding the raw edges of the strip. Fig. 5 is a sectional view transversely of the folder through 40 the forked ends of the supplemental folding member.

The folder consists of a body portion 1, which is mounted on a suitable supporting bracket 2, and said folder is preferably arranged 45 at right angles to the line of stitching and inclined at its delivery end, so that the strip passing through the folder may be inverted as it is delivered to the needle 3. This form of folder is well known in the art, and further description of the relation of 50 the folder to the needle and the inverting of the strip, is not thought necessary.

The folder 1 is provided with a central rib 4, which extends longitudinally of the 55 folder and terminates at 5, which is short of

the receiving end of the folder. The walls 6 and 7 of the folder at the receiving end thereof are arranged in a vertical line forming a single wall, so that the strip of fabric 8, which is directed to the folder will be received by the folder in unfolded vertical position. These side walls 6 and 7 of the folder are gradually bent, so as to conform to the central rib 4, as clearly shown in the drawings. 60

The walls 6 and 7 are spaced so as to form a receiving groove 9, which extends the full length of the folder, and aids in threading the strip to be folded, into the folder. The receiving end of the folder, as herein 70 shown, is bent backward, so that the strip is received at an angle to the plane of travel of the strip through the folder. This shaping of the receiving end of the folder is not, however, an essential feature, but is more 75 especially for convenience in guiding the strip to the folder.

A bracket 9' is attached to the receiving end of the folder, and is spaced therefrom, so that the strip to be folded may be guided 80 between the bracket and the wall of the folder proper. This bracket supports a supplemental guiding and folding member 10, which cooperates with the main body of the folder in turning the raw edges of the strip 85 back upon the body portion of the strip. Said guiding and folding member 10 projects forwardly from the bracket, and is made so as to yield and to produce a slight tension upon the strip as it passes through 90 the folder, through the pressure of the supplemental folder against the strip. Said supplemental folder 10 is provided with a forked end, which forms spaced fingers 11 and 11, which are located each side of the 95 receiving end of the central rib 4.

Each of the fingers 11 and 11 is curved 100 slightly outwardly at their extreme outer ends to conform to the rolling over portion of the side walls 6 and 7. The strip of fabric to be folded is passed underneath the bracket 9, and underneath the supplemental folding member 10. The strip is then inserted through the receiving slot 9, and placed in the U-shaped guiding passage of 105 the main folder. As the strip passes into the folder, the supplemental folding fingers 11 and 11 will cause the outer free edges of the strip to be bent back on to the body portion, as these fingers, together with the side walls 110

of the main folder, form a guiding channel or passage which causes the bending back of the edges.

The central rib, which at its receiving end 5 lies between the fingers 11 and 11, will gradually form the central fold in the strip, which allows the strip as it is led from the folder to be inverted and the folded raw edges concealed by the folded strip, as it is 10 placed on the fabric.

It will be apparent, therefore, that I have provided a folder which constitutes means for folding over the raw edges of a strip on to the body portion of the strip, and subsequently 15 the forming of a U-shaped central fold in the strip, which allows the strip to be inverted. By this construction, the strip may be very quickly inserted in the folder, and very small or narrow strips may be 20 operated upon by the folder, and presented to a stitching mechanism.

It is obvious that minor changes in the details of construction may be made, without departing from the spirit of the invention, 25 as set forth in the appended claims.

Having thus described my invention, what I claim as new and desire to secure by Letters Patent of the United States, is:—

1. A folder including in combination, a 30 body portion having a central rib for folding a strip, said rib terminating short of the receiving end of the folder, the walls of the folder being straight at the receiving end and gradually bent to conform to said central rib, and supplemental folding means disposed between the rib and the receiving end of the folder and coöperating with the former for turning the raw edges of the strip back on the body portion of the strip.

40 2. A folder including in combination, a body portion having a central rib for folding a strip, said rib terminating short of the receiving end of the folder, the walls of the folder being straight at the receiving end and gradually bent to conform to said central rib, and spaced fingers disposed between the rib and the receiving end of the folder coöperating with the body portion of the folder for turning the edges of the strip 45 back on the body portion of the strip.

50 3. A folder including in combination, a body portion having a central rib for folding a strip, said rib terminating short of the receiving end of the folder, the walls of the folder being straight at the receiving end and gradually bent to conform to said central rib, spaced fingers disposed between the rib and the receiving end of the folder coöperating with the body portion of the folder for turning the edges of the strip back on the body portion of the strip, and 55 means for yieldingly supporting said fingers.

4. A folder including in combination, a

body portion having a central rib for folding a strip, said rib terminating short of the 65 receiving end of the folder, the walls of the folder being straight at the receiving end and gradually bent to conform to said central rib, and spaced fingers disposed between the rib and the receiving end of the folder 70 coöperating with the body portion of the folder for turning the edges of the strip back on the body portion of the strip, the outer walls of the folder being spaced in the central plane of the folder to allow inser- 75 tion of the goods.

5. A folder including in combination, a body portion having a central rib for folding a strip, the delivery end of the folder being cut at an angle to the longitudinal 80 axis of the folder, the walls of the folder being straight at the receiving end and gradually bent to conform to said central rib, a yielding member mounted at the receiving end of the folder and having a 85 forked end forming fingers disposed on opposite sides of the rib and projecting longitudinally of the folder and located at the receiving end of the folder, said fingers co-operating with the body of the folder and 90 with the rib for turning the edges of the strip back on the body portion of the strip.

6. A folder including in combination, a body portion having a central rib for folding a strip, said rib terminating short of the 95 receiving end of the folder, spaced fingers disposed between the rib and the receiving end of the folder, said fingers extending beyond the receiving end of the rib to assist in the initial folding of the fabric.

100 7. A folder including in combination, a body portion having a central rib for folding a strip, said rib terminating short of the receiving end of the folder, spaced fingers disposed between the rib and the receiving end of the folder, said fingers extending beyond the receiving end of the rib to assist in the initial folding of the fabric, said fingers being curved to conform to the outer walls of the folder adjacent the free ends of said 110 fingers.

8. A folder including in combination, a body portion having a central rib for folding a strip, said rib terminating short of the receiving end of the folder, the wall of the 115 folder at the receiving end being straight, the outer edges of the wall being gradually bent around the rib to conform to said central rib and spaced apart to assist the threading of the strip.

120 In testimony whereof, I affix my signature, in the presence of two witnesses.

JAMES R. MOFFATT.
